UNITED STATES PATENT OFFICE.

BENJAMIN FRANKLIN CAMPBELL, OF CAMP BALDY, CALIFORNIA.

OILING DEVICE.

Application filed August 16, 1920. Serial No. 403,882.

My invention relates to the well known Model T Ford automobile. This automobile is provided with a fly wheel which is enclosed in a case and with three friction bands which are situated adjacent to the fly wheel within this case. These friction bands are used respectively to control the brake, the reverse and the low gear.

In the standard form of Ford automobile, these bands must be frequently relined due to the fact that they wear and burn out rapidly under severe service such as they are subjected to on mountain roads. They are lubricated by the splash from the fly wheel, this splash lubrication not only tending to prevent wear through the lubricating qualities of the oil, but also tending to prevent the bands from burning out due to becoming overheated. It is a well known fact, however, that in the standard form of Ford car the lubrication is insufficient to prevent burnouts where the car is given severe service. This burning out of the bands is prevented by my device which supplies a copious lubrication thereto, cooling the bands as well as lubricating them so that the life thereof is very greatly prolonged.

Further objects and advantages will be made evident hereinafter.

In the drawing which is for illustrative purposes only,

Fig. 1 is a side elevation partly in section of my device as applied to the standard Model T Ford automobile.

Fig. 2 is a plan view on an enlarged scale of the oil distributor.

Fig. 3 is a section on a plane represented by the line 3-3 of Fig. 2.

Fig. 4 is a partial side elevation of the oil deflector.

Fig. 5 is an enlarged section on a plane represented by the line 5-5 of Fig. 1.

In these drawings, the fly wheel 11 is shown inside a casing 12, the bands 13 being shown adjacent thereto. Access to the inside of the casing 12 is through a handhole in the top of the casing 12 closed by a cover 14.

In the operation of the standard Ford car, the fly wheel 11 throws up oil from a body of oil 15 in the bottom of the casing 12, this oil being splashed up against the top of the casing and some of it being thrown on the bands 12. This lubrication of the bands 12 is, however, rather accidental, somewhat uncertain especially when the oil

is partly exhausted, and I provide means for collecting the splash from the fly wheel 11 and directing it on the bands 13.

This means consists of the oil deflector 20 which is formed of a sheet of metal having a depressed portion 21 formed thereon, a flat surface 22 being left therearound. The deflector is clamped in place under the cover 14, suitable gaskets being provided between the cover 14 and the flat portion 22 and between the flat portion 22 and the ordinary bearing surface on the outside of the casing 12 against which the cover 14 is ordinarily seated. The depressed portion 21 projects through the opening into the casing 12, the upper edge 24 thereof being adjacent to the flywheel 11. The flywheel turns in the direction of the arrow shown in Fig. 2 and the edge 25 of the depressed portion 21 is cut away shown in that figure so that the oil from the flywheel can enter the depressed portion as shown in Fig. 5. This oil then runs down between the cover 14 and the depressed portion 21 being thrown through a hole 30 on top of the bands 13. A small hole 31 is provided through which an operating lever and attached parts 32 may also be oiled. The device may be readily inserted on the standard Model T Ford by simply removing the cover 14 and providing an extra gasket for clamping the portion 22 in place, the standard bolts and bolt holes being used, the portion 22 being provided with holes 35 for this purpose.

The method of operation is as follows:

The flywheel 11 turning in the direction of the arrow in Fig. 5 throws oil up against the top of the case 12, a portion of this oil being caught by the edge 25 and deflected into the space between the depressed portion 21 and the cover 14. This oil runs down inside the space and is thrown out on the top of the bands 13 which it lubricates and cools.

I have found that by the use of my invention that it is almost impossible to overheat the bands sufficiently to burn them out by any ordinary use of these bands even on excessive grades and for excessive periods.

I claim as my invention:

1. In an internal combustion engine the combination of a casing having an inclined top with a hand hole therein, a cover secured to said case and covering said hand hole, a flywheel inside said case below the

upper portion thereof said case being so formed as to deliver any oil therein to the lower portion of said flywheel, a series of friction bands adjacent to said flywheel and below said hand hole, and means inside said case for collecting the oil raised by the rotation of said flywheel and delivering it on top of said bands.

2. In an internal combustion engine the combination of a casing having an inclined top with a hand hole therein, a cover secured to said case and covering said hand hole, a flywheel inside said case below the upper portion thereof, said case being so formed as to deliver any oil therein to the lower portion of said flywheel, a series of friction bands adjacent to said flywheel and below said hand hole, a plate secured between said cover and said case, and means formed on said plate for delivering on to the top of said bands a portion of the oil raised by said flywheel.

3. In an internal combustion engine the combination of a casing having an inclined top with a hand hole therein, a cover secured to said case and covering said hand hole, a flywheel inside said case below the upper portion thereof, said case being so formed as to deliver any oil therein to the lower portion of said flywheel, a series of friction bands adjacent to said flywheel and below said hand hole, a plate secured between said cover and said case, a depressed portion formed on said plate and extending through said hand hole into said casing, means on said depressed portion for collecting a portion of the oil raised by the rotation of said flywheel, and means for delivering said portion of said oil on top of said bands.

4. In an internal combustion engine the combination of a casing having an inclined top with a hand hole therein, a cover secured to said case and covering said hand hole, a flywheel inside said case below the

upper portion thereof, said case being so formed as to deliver any oil therein to the lower portion of said flywheel, a series of friction bands adjacent to said flywheel and below said hand hole, a plate secured between said cover and said case, a depressed portion formed on said plate and extending through said hand hole into said casing, a lip formed on said depressed portion and located adjacent to said flywheel for collecting a portion of the oil raised by the rotation of said flywheel, and means for delivering said portion of said oil on top of said bands.

5. In combination with a housing containing a fly wheel and transmission mechanism, a pan located in the upper portion of the housing above the transmission mechanism and adjacent to the upper portion of the fly wheel and adapted to receive oil splashed from the fly wheel, said pan being apertured to allow oil to pass therefrom to the transmission mechanism.

6. In combination with a housing containing a fly wheel and transmission mechanism, a pan located in the upper portion of the housing above the transmission mechanism and adjacent to the upper portion of the fly wheel and adapted to receive oil splashed from the fly wheel, said pan being adapted to allow oil to pass therefrom to the transmission mechanism.

7. In combination with a housing containing a fly wheel and transmission mechanism means located in the upper portion of the housing and adjacent to the upper portion of the fly wheel, said means being adapted to intercept and convey oil splashed from the fly wheel to the transmission mechanism.

In testimony whereof, I have hereunto set my hand at Los Angeles, California, this 9th day of August 1920.

BENJAMIN FRANKLIN CAMPBELL
